UNITED STATES PATENT OFFICE.

JOHN R. SCHWIETERS, OF BETTENDORF, IOWA.

COMBINED MOP AND SCRUB-BRUSH.

1,177,820.

Specification of Letters Patent.

Patented Apr. 4, 1916.

Application filed August 31, 1915. Serial No. 48,242.

To all whom it may concern:

Be it known that I, JOHN R. SCHWIETERS, a citizen of the United States, residing at Bettendorf, in the county of Scott and State 5 of Iowa, have invented a new and useful Combined Mop and Scrub-Brush, of which the following is a specification.

This invention relates to a combined mop and scrub brush, one of the objects of the 10 invention being to provide a simple and efficient means whereby a mop cloth can be held in either active or inactive position relatively to a scrub brush, the means provided for this purpose being cheap to manufacture and efficient in use.

A further object is to provide a device of this character which is so constructed as to allow the mop cloth to be placed in an ordinary mop wringer.

20 Another object is to provide a means for detachably holding a scrub brush so that a new brush can be placed in position whenever desired.

A further object is to provide a combined 25 mop and scrub brush which is light and can be handled easily.

With the foregoing and other objects in view which will appear as the description proceeds, the invention resides in the combination and arrangement of parts and in the details of construction hereinafter described and claimed, it being understood that changes in the precise embodiment of the invention herein disclosed, can be made 35 within the scope of what is claimed, without departing from the spirit of the invention.

In the accompanying drawings the preferred form of the invention has been shown.

In said drawings: Figure 1 is a side elevation of the device in position for use as a mop. Fig. 2 is a like view showing the same in position for use as a scrub brush. Fig. 3 is a plan view of the device with the parts in the position shown in Fig. 2, the 40 mop cloth being removed. Fig. 4 is a perspective view of the head for holding a scrub brush and one end of a mop cloth. Fig. 5 is a plan view of the spring holding clip.

Referring to the figures by characters of 50 reference 1 designates a handle on one end of which is mounted a ferrule and stem 2 extending from a plate 3. This plate is disposed at an acute angle to the end of the handle 1 and has spring arms 4 diverging 55 from the corner portions thereof. The arms are disposed in pairs, the outer ends of the

arms of one pair being turned toward the outer ends of the opposed arms. These outer inturned ends of the arms of each pair are connected by retaining wires 5 preferably integral with the arms. As shown in Fig. 1 the back 6 of a scrub brush is adapted to be inserted between the two pairs of arms 4, the inturned end portions of these arms and the retaining wires 5 engaging 60 that face of the back from which the bristles 7 of the brush project. Thus the brush will be held securely to the handle 1 and, should it be desired to remove it for any purpose, it would merely be necessary to 65 force it laterally from between the arms 4.

Projecting from the outer end of the plate 3 is an angular loop 8 having a straight intermediate portion which extends through one end of a mop cloth 9 preferably 70 formed of a strip of fabric the ends of which are secured together. This mop cloth 9 also engages a loop 10 provided at one end of an arm 11 which is pivotally connected, as at 75 12, to a clip 13 embracing the handle 1 and clamped thereon in any desirable manner, as by means of a bolt 14 which bolt can also constitute the pivot of the arm 11. Ears 80 15 extend laterally from the clip and each ear is connected by a spring 16 to an intermediate portion of the arm 11. These springs are so positioned as to hold the arm 11 normally pressed against the handle 1 when extended either upwardly or downwardly from the clip 13. When the arm 11 85 is extended upwardly along handle 1, as shown in Fig. 2, the mop cloth 9 will be held extended above the handle 1 so that the brush can thus be held for scrubbing without interference by the mop cloth. 90 However, should it be desired to use the mop cloth, it would merely be necessary to invert the structure to the position shown in Fig. 1, first pushing the arm 11 past its pivot 95 14 so as to cause the springs 16 to hold the arm in the position shown in Fig. 1. The plate 3 has the wires secured to it in any manner desired. It has been the practice to utilize a retaining plate 17 which is fastened to the plate 3 by means of rivets or the like, 100 the wires being clamped between the two plates.

What is claimed is:—

1. The combination with a handle and means for detachably securing a brush to 110 one end of the handle, of an arm pivotally connected to the handle, a loop upon the

arm, a loop extending from and fixed relative to the brush securing means, a mop cloth secured to the two loops, yielding means connecting the handle and the arm 5 for holding said arm extended in either of two directions along the handle, said cloth being held folded beyond one end of the handle when the arm is in one position and stretched along the handle when the arm is 10 in its other position.

2. The combination with a handle, a plate connected to one end thereof and disposed at an angle thereto, and brush gripping means extending from the plate, of a loop 15 projecting from said plate, a clip secured to the handle, an arm pivotally connected to

the clip and having a loop at one end, a mop cloth mounted at its ends upon the two loops, a spring connection between the arm and the clip for holding said arm in either 20 of two positions along the handle thereby to hold the mop cloth in folded position beyond the end of the handle or stretched longitudinally along the handle.

In testimony that I claim the foregoing as 25 my own, I have hereto affixed my signature in the presence of two witnesses.

JOHN R. SCHWIETERS.
